RAILWAY CROSSING BAR

Owen E. Manley, Springfield, Ill.

Application February 13, 1948, Serial No. 8,032

11 Claims. (Cl. 238—8)

1

This invention concerns intersections of railroads and highways and in particular refers to crossing bars which fill the spaces between the rails and the roadway.

As is common knowledge, in the construction of rail-street intersections, a considerable gap or space is left between the inner edge of the rail and the roadway fill between the tracks, in order to accommodate passage of the flanged wheels of railway rolling stock. This gap causes an uneven roadway and vehicles passing over the rails are often subject to very appreciable jars and bumps. In addition to the stresses placed upon the vehicles crossing such intersections and discomfort to the occupants thereof, the forces created by the uneven passage of trucks and automobiles have a cumulative effect which is harmful to the roadbed. Thus, if the center fill between the tracks comprises a series of planks, these soon become loosened and damaged. If the fill is paving or gravel, it is, in time, broken up or scattered so that the uneven condition becomes more aggravated.

In view of the modern tendency toward higher vehicle speeds, there has been an increasing demand for means to eliminate the foregoing conditions and it is an object of my invention to meet this demand by providing a railway crossing bar which is adapted to fill the space between the rail tracks and the roadway. Another object is to provide a crossing bar which evens the roadway, but which does not interfere with the passage of trains along the track.

It will be recognized that the desire to fill the spaces heretofore referred to is in conflict with the requirement that a space be provided along the edge of the rail to receive the flanges of the wheels of the trains. To overcome this difficulty, I provide a safety bar which is fixedly positioned flush with the tops of the rails but which, upon suitable actuation, is capable of downward movement to leave space for the wheel flanges. In the preferred form of my invention, the bar is normally held in a fixed position by a lower support member which has upright legs engaging downwardly extending legs on the cross bar. The support member is capable of sliding movement along the track to permit disengagement of the legs and allow the crossing bar to be forced downward against springs by the flanges of the train wheels. Sliding movement of the support member is actuated by the wheel flanges acting upon a novel linkage which is constructed and arranged to change the substantially vertical forces applied thereto by the

2

wheels into horizontal forces for moving the support member.

The foregoing and other features and objects of my invention will become apparent after a consideration of the accompanying drawings in which:

Figure 1 is a plan view of the rail-street intersection to which the invention might be applied.

Figure 2 is a top plan view of the invention and includes a portion of a rail.

Figure 3 is a side elevation taken along a plane between the rail and the improved crossing bar and shows the bar in elevated position.

Figure 4 is a view similar to that of Figure 3. It has parts broken away to show the central portion of the novel linkage and it shows the cross bar in depressed position to accommodate passage of a train.

Figure 5 is an enlarged cross section taken along the line of 5—5 of Figure 4 and includes a portion of the rail and roadway.

Figure 6 is an enlarged cross section taken along the line of 6—6 of Figure 3 and includes a portion of the rail and roadway.

Figure 7 is an enlarged side elevation of a portion of the mechanism.

Figure 8 is a top plan view of the structure shown in Figure 7.

Figure 9 is a cross section of a modified form of the invention.

Referring to the drawings, Figure 1 shows the intersection of a roadway and a railway. As is well known, the roadway is substantially flush with the tops of the rails A so that it is necessary to leave grooves S between the inner edges of the rails A and the roadway to permit passage of the flanged train wheels. The grooves S between each pair of rails thus define the outer edges of the fill between the tracks. The wheels of vehicles travelling along the roadway strike the edge of these grooves S and these forces, in addition to jarring the vehicle, result in the eventual destruction of the fill.

My invention, as shown in plan in Figure 2, is adapted to fit into the grooves S which are adjacent to the rails A and includes a vertically movable crossing bar 1 which in its inoperative position, as shown in Figures 2, 3, and 6, is substantially flush with the top of the rail A and therefore prevents the jarring and striking forces just referred to.

In the preferred form of my invention, the crossing bar 1 is similar to an angle bar and has a transverse or horizontal flange 3 which is

adapted to fill the groove S. The vertical side, or web 5 of the bar 1, is recessed at intervals to form a plurality of spaced legs 7. The web 5 also has a plurality of spaced, vertical slots 9.

The bar 1 is guidably connected to a carrier plate 11 by means of the transverse pins 13 in the plate which extend through the vertical slots 9. The plate 11 has a vertical side 15 and a horizontal side 17 which may be joined by reinforcing ribs 19. The vertical side 15 of the carrier plate 11 forms one side of the space 5, the rail A forming the other, and is preferably of such length that the horizontal side 17 rests practically on the railroad ties.

The bar 1 is supported or locked in fixed, elevated position by a support member 21. This member preferably is a vertical plate which is recessed on its upper side to form a plurality of spaced legs 23 which are in alignment with and engaging the legs 7 of the bar 1 while inoperative. The support member 21 has a plurality of horizontal slots 25 for a purpose to be presently described.

The support member 21 is slidably mounted for longitudinal or horizontal movement parallel to the rail A and the bar 1. For this purpose, there are provided a plurality of upright support brackets 27 which are inwardly spaced from the carrier plate 11. I prefer to construct these brackets so that the lower portions thereof taper toward the plate 11, whereby they may be fixedly connected thereto, as by welding, as shown at 29. The member 21 is positioned between the brackets 27 and the plate 11. A plurality of transverse pins 31 are journaled in the brackets 27 and carrier plate 11 and extend through the horizontal slots 25 in the member. The member 21 is thus capable of horizontal, but not vertical, movement. I prefer to mount rollers 33 on the pins 31 to ride in the slots 25 and thereby facilitate horizontal movement.

Horizontal movement of the support members is actuated by the wheel flange of an approaching train acting through suitable linkage connected to the member. This linkage may take several different forms, the criterion being that it be capable of transferring a downward thrust by the wheel into a horizontal force on the support member 21. The linkage which I prefer includes a central rocker arm 35 which is pivoted at substantially its midpoint to the middle bracket 27, as by the pin 31. A horizontally and upwardly extending link 39 is pivotally connected at its lower end to the lower end of the rocker arm, as shown at 41, and at its upper end, to the support member 21, as shown at 43. Long longitudinal links 45 and 47 are pivotally connected respectively to the upper and lower ends of the rocker arm 35, as shown at 49 and 41, and extend out in either direction beyond the ends of the bar 1 and the support 21 and hence, beyond the sides of the roadway.

The links 45 and 47 are actuated by identical sub-systems of linkages 50 hence, only one will be described. Each sub-system has a guide arm 51 which is pivotally connected to the outer ends of the links, as shown at 53, and also to the carrier plate 11 at a point 55 which is inward toward the edge of the road with respect to the connection 53. A substantially vertical link 57 is also pivotally connected to the arm 51 and the link 45 or 47 at the point 53. This link, as shown in Fig. 3, has its upper end disposed close to the top of the plate 11 and bar 1, so that it will be contacted and depressed by the flange of a

train wheel on the rail A. The upper end of the link 57 is pivotally connected at 59 to a substantially longitudinal guide arm 61 which is pivoted to the plate 11 at its outermost end as indicated at 63.

Two means are provided for yieldably holding the mechanism just described in the position shown in Figure 3, i. e., the position in which the bar 1 is elevated to form a part of the roadway. In my preferred form the first of these means comprises a coil spring 65 which is connected to the carrier plate 11, as shown at 67, and to a suitable point in the linkage, for example, the point 53, so that it yieldably biases the support member 21 to the position of Figure 3 in which the legs 23 are in alignment with the legs 7 of the bar 1. The second means comprises the springs 69 which are compressed between the flange 3 of the bar 1 and flanges 71 on the brackets 27, so that they urge the bar 1 upwardly to the elevated position of Figure 3. Pins 73 may be provided on the flanges 3 and 71 for confining the springs 69 to predetermined positions.

In operation, the mechanism heretofore described is in the position of Figure 3 while inoperative. In this position the bar 1 is rigidly held so that its flange 3 fills the groove S and smooths the roadway by means of the cooperating legs 7 and 23. When a train approaches along the rails A, however, a wheel flange rides along the arm 61 and depresses the link 57. This forces the linkage to rotate about the fixed point 55 and moves the links 45 and 47 inwardly toward the center of the road. This movement causes the rocker arm 35 to pivot about its center 33 in a clockwise direction. As the arm 35 moves in this direction, it carries the link 39 inwardly toward the left in Figures 3 and 4. Since the link 39 is attached at 43 to the support member 21, its movement to the left slides this member leftward on the rollers 33 so that the ends of legs 23 become disengaged from the ends of the legs 7. When this occurs, the springs 69 supply the only resistance to depression of the bar 1 from its elevated position. When the flange of the train wheel rides over the bar 1, it therefore depresses it as shown in Figure 4 and passes without interference across the roadway in the groove S. After the train has passed, the springs 69 force the bar 1 to its elevated flush position and the tension in spring 65 is transmitted through the link 47 to rotate the arm in a counterclockwise direction. This slides the support member to the right and legs 7 and 23 are brought into alignment to positively prevent depression of the bar 1. If desired, the edges of the legs 7 and 23 may be rounded as shown at 75 to facilitate the reengagement of the legs.

In the modified form of my invention, shown in Figure 9, the aforescribed structure is not changed, but a housing 101 is included to encase the bar 1 and support member 21. This is adapted to accommodate vertical movement of the crossing bar 1 and for this purpose comprises two sections which are movable relative to each other. I prefer to have a lower trough-like section 103 and upper parallel plates 105 fixedly attached to the inner and outer edge of the flange 3 on the bar 1. These plates may be slidably connected in a suitable manner to the side walls of the section 103, as by a pin and slot connection (not shown), so that they move freely with the bar 1. The parts within the housing 101, as defined by the plates 105, the trough section 103, and the bar flange 3, are thus substantially protected from dirt, stones, and other undesirable

foreign elements. If desired, the housing may be substantially filled with a suitable lubricant, preferably solid, such as graphite, as shown at 107.

From the foregoing description, it will be evident that I have accomplished the objects of my invention by providing a novel and effective mechanism for evening rail and street intersections. It will be understood, of course, that the specific features and structures described may be modified without departing from the invention as defined by the appended claims. In particular it may be noted that, if desired, the carrier plate 11 may be eliminated in many applications and the remaining mechanism reversed and connected to the web of the rail A by means of the pins 13, 31 and connection 29.

I claim:

1. In a railway crossing bar mechanism, an upper member adapted to substantially fill the space between a rail and a roadway, said upper member being capable of movement downward between a rail and roadway, a lower support member operatively connected to the upper member so as to prevent downward movement thereof, means whereby the members may be disconnected to permit downward movement of the upper member, and force transmitting means operatively connected to the aforementioned means for actuating the same to disconnect the members, said force transmitting means being constructed and arranged to transmit disconnecting forces when contacted by the wheel of a train passing along the rail.

2. In a railway crossing bar mechanism, an upper member adapted to substantially fill the space between a rail and roadway and having a plurality of spaced downwardly extending legs, said upper member being capable of downward movement, a lower support member having a plurality of spaced upwardly extending legs engaging the aforementioned legs whereby the lower member prevents downward movement of the upper member, one of the members being movable transversely whereby the legs are disengaged, means adapted to be actuated by a train wheel for moving the one member transversely.

3. A mechanism as claimed in claim 2 including resilient means for resisting downward movement of the upper member.

4. In a railway crossing bar mechanism, an upper member adapted to substantially fill the space between the rail and a roadway and having a plurality of spaced downwardly extending legs, said upper member being capable of downward movement, a lower support member having a plurality of spaced upwardly extending legs normally engaging the aforementioned legs whereby the lower member prevents downward movement of the upper member, said lower member being capable of transverse movement whereby the legs are disengaged, and linkage adapted to be actuated by the train wheels connected to the lower member for moving the same transversely to disengage said legs.

5. In a railway crossing bar mechanism, an upper member adapted to substantially fill the space between a rail and a roadway, said member being capable of downward movement, a lower support member, means operatively connecting said members to prevent downward movement of the upper member, said lower support member being capable of horizontal movement, said means being constructed and arranged so as to be disconnected by such horizontal movement,

and means connected to the lower member for actuating transverse movement, said last means being arranged to be actuated by the wheels of a train on the rail.

5 6. In a railway crossing bar mechanism, a yieldable member adapted to substantially fill the space between a rail and a roadway, locking means for holding the member in a fixed position substantially flush with said roadway, and means operatively associated with said locking means capable of actuation by a passing train for unlocking the locking means.

15 7. A railway crossing bar mechanism comprising a vertically movable upper member adapted to substantially fill the space between a rail and roadway means yieldably biasing the member to an upward position, a horizontally movable lower member capable when in one position of fixedly supporting the upper member so that it is substantially flush with a roadway means yieldably biasing the lower member to said one position, and means capable of actuation by a passing train for horizontally moving the lower member against said last means away from the one position to permit downward movement of the upper member against the first means when a train passes thereover.

20 8. In a railway crossing bar mechanism for insertion in the space between a rail and a roadway, an elongated carrier plate, a space filling member slidably mounted on the carrier plate for movement transverse to the major dimension thereof, a support member slidably mounted on the carrier plate beneath the other member for longitudinal movement with respect to the plate, said members having alternate protuberances and recesses normally arranged so that the protuberances are in engagement whereby the support member prevents longitudinal movement of the other member, and means capable of actuation by the wheels of a train for slidably moving the support member to disengage the protuberances and cause them to be in alignment with recesses thereby permitting longitudinal movement of the space filling member.

25 9. In a railway crossing bar mechanism for insertion in a groove between a rail and a roadway, an upper member adapted to substantially fill the space between a rail and roadway, a lower support member, an elongated carrier plate, means connecting the upper member to the plate for limited vertical movement, means connecting the lower member to the plate for limited longitudinal movement, interengaging means on said members arranged so that when the members are in predetermined positions relative to each other the lower member prevents downward movement of the upper member, a movable link arranged so that a portion thereof is adjacent to and substantially flush with the top of a rail, a pivoted rocker arm, a link pivotally connected to the rocker arm and to the lower member, and linkage connecting the movable link to the rocker arm whereby a downward thrust thereon by a train wheel actuates the arm and attached link to move the lower member to a position wherein downward movement of the upper member is permitted.

30 10. A device for filling gaps or the like comprising, in combination, an elongated filler member capable of vertical movement, means yieldably urging the member to one vertical position, movable support means operative in one position to prevent vertical movement of the member in one direction but rendered inoperative by move-

ment to another position, means yieldably urging the support means to said one operative position, an actuator spaced beyond one end of the filler member and capable of longitudinal movement, and means operatively connecting the actuator to the support means so that the longitudinal movement of the actuator in one direction moves the support means to an inoperative position to permit vertical movement of said filler member in the one direction.

11. In a railway crossing bar mechanism the combination of a vertically movable elongated upper member adapted to substantially fill the space between a rail and roadway, a longitudinally movable elongated lower member capable in one position of fixedly supporting the upper member against vertical movement in one direction, a housing encasing the members having a portion thereof vertically movable with the upper

member, and means capable of actuation by a passing train for longitudinally moving the lower member away from the one position to permit vertical movement of the upper member.
